US0D1042128S

(12) **United States Design Patent** (10) Patent No.: **US D1,042,128 S**
Li (45) Date of Patent: ** Sep. 17, 2024

(54) **BOTTLE STOPPER**

(71) Applicant: **Frandroid Sarl**, Neuilly-sur-Seine (FR)

(72) Inventor: **Wenqiang Li**, Guangxi (CN)

(**) Term: **15 Years**

(21) Appl. No.: **29/921,857**

(22) Filed: **Dec. 19, 2023**

(51) LOC (14) Cl. **09-07**

(52) U.S. Cl.

CLAIM

The ornamental design for a bottle stopper, as shown and described.

DESCRIPTION

FIG. 1 is a perspective view of the bottle stopper showing my new design;

FIG. 2 is another perspective view of the bottle stopper showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures illustrate portions of a bottle stopper that form no part of the claimed design.

1 Claim, 8 Drawing Sheets
